UNITED STATES PATENT OFFICE.

ANTON GOETZ, OF BERWICK, NORTH DAKOTA.

SCRAPER FOR DISK DRILLS.

1,113,776.

Specification of Letters Patent. Patented Oct. 13, 1914.

Application filed May 1, 1914. Serial No. 833,615.

To all whom it may concern:

Be it known that I, ANTON GOETZ, a citizen of the United States, residing at Berwick, in the county of McHenry and State 5 of North Dakota, have invented certain new and useful Improvements in Scrapers for Disk Drills, of which the following is a specification.

The present invention relates to certain 10 new and useful improvements in the construction of scrapers for disk drills, the object of the invention being to provide a device of this character which can be readily attached to an ordinary disk drill and which 15 embodies novel features of construction whereby it serves both as a scraper and also to hold the forward edges of the disks in a yielding contact so that the drill will act in an effective manner to drill the grain well 20 into the seed bed.

A further object of the invention is to provide a scraper for disk drills which is comparatively simple and inexpensive in its construction, which automatically compensates for wear, which does not increase 25 the draft or interfere with the usual operation of the drill, and which can be adjusted according to the space between the 30 drill disks.

With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawings, in which:—

Figure 1 is a side elevation of a disk drill provided with a scraper constructed in accordance with the invention, one of the disks being removed to bring out more clearly the manner of mounting the scraper between the disks. Fig. 2 is a rear view of a disk drill provided with the scraper. Fig. 3 is a sectional view on the line 3—3 of Fig. 1, showing the manner in which the scraper engages the disks. Fig. 4 is a detail view 50 of the scraper detached.

Corresponding and like parts are referred to in the following description and indicated in all the views of the drawings by the same reference characters.

For the purpose of illustration the scraper has been illustrated as applied to a

conventional form of disk drill which will only be described in a very general manner since it constitutes no part of the present invention.

The numeral 1 designates the boot of the disk drill which is arranged at the top of the disks 2, the forward end of the boot terminating in an arm 3 to which a draw bar can be attached, while the rear end of the boot 60 carries a bracket 4 which projects between the disks and upon which the inside scraper is mounted. The standard 5 projects downwardly from the boot 1 and has the disks 2 journaled thereon by means of 65 suitable bearings 6. The disks diverge rearwardly in the usual manner with the forward edges thereof in contact with each other, the bearing 6 being of such a nature as to admit of the edges of the disk being 70 always maintained flexibly in contact as they become worn and decrease in diameter. The usual seed spout 7 passes downwardly through the boot 1 at the rear of the standard 5, and a deflector 8 is shown as disposed 75 at the rear of the seed spout 7 so as to cause the grain to drop in the most effective manner.

The scraper includes a pair of scraping bars 9 which have a spring 10 interposed between the lower and inner ends thereof, the extremities of the spring receiving and being engaged by suitable positioning lugs 11. Projecting laterally from each of the scraping bars 9 near the opposite end thereof is a 80 pivot arm 12, the two arms overlapping each other and being connected by the pivot bolt 13 which also serves to secure the scraper to the bracket or arm 4 at the rear 85 end of the boot 1. The spring 10 forces the scraping bars 9 outwardly so as to hold them in a yielding contact with the inner faces of the two disks 2. As the disks 90 revolve the bars 9 act in the usual manner to scrape the dirt therefrom and the yielding action of the spring 10 tends to force the rear edges of the disks 2 apart and hold the forward edges thereof in a flexible engagement with each other. The action of the 95 spring 10 also serves to compensate for wear 100 upon the scraping bars, since as the bars become worn they are forced farther apart so as to always be held against the sides of the disks 1 with the same degree of pressure.

The lateral arms 12 are preferably adjustably connected to the scraping bars 9 so

that they can be moved in and out thereon to admit of the scraper being properly adjusted for any disk drill. For this purpose the arms 12 are shown as formed with slots 15 engaged by clamping bolts 16. When the bolts 16 are loose the lateral arms 12 can be shifted in and out so as to draw the scraping bars 9 together or throw them farther apart according to the space between the rear edges of the disks on the particular drill to which the scraper is to be attached. After the arms 12 have been properly adjusted upon the respective scraping bars 9, they are pivotally connected by the bolt 13 and attached by the same bolt to the inwardly projecting arm 4 at the rear end of the boot 1. When in position the scraping bars 9 are disposed between the two disks 1 and maintained in a yielding contact therewith by means of the spring 10, as previously described. The upper ends of the scraping bars 9 are shown as cut away at 9^a to insure a proper clearance of the rear end of the boot and prevent any interference thereof with the proper operation of the scraper.

Having thus described the invention, what I claim as new and desire to secure by Letters Patent, is:—

- 30 1. The combination of a disk drill having a scraper supporting arm on the boot thereof, a pair of scraping bars arranged between the disks, lateral arms projecting from the scraping bars, means for pivotally connecting the lateral arms to the scraper supporting arm of the boot, and a spring interposed between the scraper bars to swing the same apart and hold them in yielding engagement with the disks.
- 35 2. The combination of a disk drill having a scraper supporting arm upon the boot thereof, a pair of scraper bars arranged between the disks, lateral arms projecting from the scraper bars, means for adjustably connecting the lateral arms to the respective

scraper bars so that they can be moved in and out thereon, means for pivotally connecting the lateral arm and mounting the device upon the scraper supporting arm of the boot, and yielding means acting upon the scraper bars to swing them apart and hold them in a yielding engagement with the disks.

3. The combination of a disk drill having a scraper supporting arm projecting from the boot thereof, a pair of scraping bars arranged between the disks, lateral arms projecting from the scraping bars toward one end thereof, positioning pins projecting from the scraping bars at the opposite ends thereof, means for pivotally connecting the lateral arm and mounting the device upon the scraper supporting arm of the boot, and a spring interposed between the scraper bars and engaging the positioning pins thereof, said spring serving to swing the scraper bars apart and hold them in a yielding engagement with the disks.

4. The combination of a disk drill having a scraper supporting arm projecting from the boot thereof, a pair of scraper bars interposed between the disks, lateral arms projecting from the scraper bars, means for adjustably connecting the lateral arms to the scraper bars so that they can be moved in and out with respect thereto, a bolt pivotally connecting the lateral arms and engaging the scraper supporting arm of the boot, positioning pins projecting from the scraper bars, and a spring interposed between the scraper bars and engaging the positioning pins thereof, said spring serving to swing the scraper bars apart and hold them in a yielding engagement with the disks.

In testimony whereof I affix my signature in presence of two witnesses.

ANTON GOETZ.
